UNITED STATES PATENT OFFICE.

CHARLES S. WILLIAMSON, OF CHICAGO, ILLINOIS.

APPARATUS FOR HANDLING COAL, ORE, AND THE LIKE.

1,392,382.

Specification of Letters Patent.

Patented Oct. 4, 1921.

Application filed August 9, 1917. Serial No. 185,402.

To all whom it may concern:

Be it known that I, CHARLES S. WILLIAMSON, a citizen of the United States, residing at Chicago, in the county of Cook and State 5 of Illinois, have invented certain new and useful Improvements in Apparatus for Handling Coal, Ore, and the like, of which the following is a specification.

This invention relates to a method and 10 apparatus for transferring and simultaneously weighing iron ore, coal, or other bulky material from a source of supply to a car.

It is an object of my invention to provide a method whereby the product being 15 transferred may be weighed in transit from the source of supply to the car without in any way interrupting or stopping the mechanism which transfers the product from the source of supply.

20 A further object of my invention is to provide means whereby cars on any of several parallel tracks may be initially loaded to an exact predetermined maximum.

25 A further object of my invention is to provide means whereby a predetermined amount of product may be delivered at a desired point without in any way interrupting or stopping the mechanism which transfers the product from the source of supply.

30 A further object is to provide means for transferring the product from a boat or from a supply from the dock to a railroad car or cars and delivering to the car or cars a predetermined amount during the initial 35 loading without interrupting the operation of the transferring mechanism from the source of supply.

The above and other features of novelty, 40 advantages and capabilities will become apparent from a detailed description of the accompanying drawings, in which I have illustrated a device embodying one form of my invention, but the construction there shown is to be understood as illustrative 45 only, and not defining the limit of my invention.

In the embodiment shown, the handling 50 bridge is designed to unload boats positioned beside the docks, and deliver the product either to docks or a receiving hopper, which hopper is supported on the water side pier of the bridge, from which hopper the product is ultimately delivered to railroad 55 cars for shipment, a large percentage of the product in practice will be delivered to the cars without being deposited on the

docks, but where there is a shortage of cars, or where the disposition of the product has not been determined, a large percentage of the product will be deposited on the docks. 60

All railroad cars are required to be loaded below a certain definite maximum weight. Therefore, in order to save handling charges, it is necessary to load all cars to the exact limit, for anything less than a car-load requires the same handling charges as a car loaded to its maximum limit, particularly on such commodities as iron ore. Therefore, it is necessary to load the cars accurately. 70

With the devices now in use such as stationary track scales on a large dock, which is located at the outlet end of the dock, it is necessary that all cars from all points pass over the dock scales where they are weighed. 75 With such arrangement in order to load the car to its maximum limit, it is necessary to adjust the load at the stationary scales either by adding more product to the contents of the car, or by taking out in case of 80 an over run. This is unsatisfactory, inconvenient, laborious and expensive. With my invention, the correct amount can be predetermined and put into the car at the initial loading without in any way interrupting the operation of the mechanism carrying the product from the boat or source of supply. This latter feature is also very important, for with it the maximum amount of work or results can be had from the 85 transferring mechanism which carries the product from the boat or dock, and from the men who operate such mechanism.

Referring to the drawings:

Figure 1 is an elevational view of the 95 device embodying one form of my invention, showing it in position on a dock ready for use.

Fig. 2 is a plan view of the same showing a boat alongside the dock. 100

Fig. 3 is an enlarged detail view of the water side pier and parts in connection therewith, showing the receiving hopper, weighing lorry, and boat partly in section.

The frame 10 of the traveling bridge is 105 of the well known and usual construction, and is supported by two piers 11 and 12. The water side pier 11 has two supporting legs 13, which straddle a series of railroad tracks, which in the drawings are shown four 110 in number. The pier 12 and the supporting legs 13 are each provided with the usual

wheel trucks operable in the usual manner on the tracks, as shown for moving the entire bridge over the tracks when desired.

Supported by the water pier 11 is a receiving hopper 14, which in commercial practice may be of sufficient size to contain one hundred tons of ore. The receiving hopper 14 is provided in the bottom with gates 15, which are power operated by any well known means, and are under control of the operator in the cab 16, which gates when operated gradually discharge into the hopper 17^a on the traveling weighing lorry 17, which lorry is provided with a weighing scales, the scale beam of which is in the cab 16. The bottom of the hopper on the lorry is provided with gates for discharging the product from the lorry into the cars 18. The traveling lorry as a whole is supported on trucks designed to travel on tracks 19 over the cars 18, so that it can be moved to register with a car on any one of the tracks. The movement of the lorry as a whole, as well as the gates for discharging, are power operated in any well known manner, and are under the control of the operator in the cab 16. The bridge is provided with the usual grab bucket 20, which is operated in any well known manner, and is designed to carry the product from the boat 21 beside the dock directly to the receiving hopper, or to a place on the dock, for example, as shown at 22 in Fig. 1.

In commercial practice, the traveling bridge is usually served by several railroad tracks, for example, as shown in the drawings. Therefore, it is desirable to load accurately into the cars on any one of the tracks, and it may be absolutely necessary to do this without moving the bridge, as the bridge is apt to be operating in a definite hatch in the boat alongside the dock, and therefore the grab bucket must return at each trip to exactly the same position in the boat. With my invention this can be done.

In the operation of the device embodying my invention, as illustrated in the drawings, the product is unloaded either from the boats or taken from the docks by means of the grab bucket 20, and delivered to the receiving hopper 14. From the receiving hopper, the operator in the traveling weighing lorry cab 16 draws off the ore or other product in the receiving hopper into a hopper 17^a carried on the scales on the weighing lorry, which weighing lorry is carried on a series of trucks as shown, and designed to be moved over the tracks 19 transversely of the railroad tracks. The operator in the cab 16 sets the scale beam at the desired amount of ore or other product, either at one-half of the load or other portion of the load, which he desires to load into the railroad cars, and then operates the gates on

the receiving hopper 14, which gradually discharge into the hopper on the weighing scales until the predetermined amount is reached. The gates are then thrown out of operation and the weighing lorry moved to position over the car which is to be loaded. The operator then opens the gates in the bottom of the hopper 17^a and discharges the contents in the car below.

A great many railroad cars are designed to carry fifty-five tons of ore. As these cars are preferably loaded in two piles, one over each set of trucks, the weighing lorry in commercial practice is of a sufficient size to hold practically one-half a railroad car, or about thirty tons. If a car to be loaded has a maximum rated capacity of fifty-five tons, the operator sets the scale beam at twenty-seven and one-half tons, and then draws off ore from the receiving hopper until the scale beam exactly balances. He then shuts off the supply of ore from the receiving hopper, and operates the weighing lorry until it registers directly over the railroad track upon which the car is located to be loaded. He then deposits the twenty-seven and one-half tons of ore which the lorry contains into the railroad car, approximately over one of the end trucks. He then travels back to the receiving hopper and draws off another lot amounting to twenty-seven and one-half tons, and again moves back over the railroad car to be loaded. In the mean time, the railroad car has been moved along until the other truck 100 stands beneath the discharge of the weighing lorry, and when the operator discharges the second charge of twenty-seven and one-half tons, it is deposited in the opposite end of the car from that in which the first charge was delivered, and the car is then initially loaded to its predetermined maximum capacity.

It is obvious, of course, that very much larger cars may be built, so that it would require more than two trips of the weighing lorry to fill the car, or the size of the weighing lorry may be increased. I have merely referred to cars and weighing lorries of the size mentioned to bring out more clearly the ease and manner of loading with my invention under the present commercial practice. All operations, of the gates in the receiving hopper 14, and of the weighing lorry, including the weighing of the product, is handled by the operator in the cab 16. It is readily seen from the description and illustration that the operation of conveying or transferring the product, either from the boat or dock can be carried on continuously without interruption while the weighing lorry is being operated.

Having now described my invention, I claim:

1. In a plant of the class described, a

- bridge, tracks supporting said bridge, a receiving hopper fixed with relation to the bridge, a lifting bucket, traveling relatively to the bridge and hopper, a weighing lorry, 5 traveling transversely to the tracks, readily controllable means for gradually feeding the products from the receiving hopper to the weighing lorry, and means for discharging from the weighing lorry.
- 10 2. In a plant of the class described, a handling bridge supported on rails, a large elevated receiving hopper supported rigidly with relation to the bridge, means for conveying the product from a source of supply 15 to the receiving hopper, a weighing lorry supported by the bridge below the receiving hopper, adjacent thereto and capable of traveling transversely of the tracks, readily controllable means for gradually feeding 20 the product, as desired, from the receiving hopper to the weighing lorry, and means for discharging the product from the weighing lorry to a car below.
3. In a plant of the class described, means 25 for initially loading a car to a predetermined maximum, said means comprising a bridge, a large elevated receiving hopper fixedly supported on the bridge, a lifting bucket for conveying the product from a source of supply 30 to the receiving hopper, a weighing lorry supported on the bridge below the receiving hopper for traveling movement relatively to the bridge, readily controllable means for gradually feeding and instantly stopping the feeding of the product from the receiving 35 hopper to the weighing lorry, and means for discharging the product from the weighing lorry to a car on any one of a plurality of tracks beneath the bridge.
- 40 4. In a device of the class described, a bridge, a track supported on the bridge above a series of railroad tracks, and transversely thereto, a traveling weighing lorry designed to travel on said first mentioned 45 track, a receiving hopper fixedly supported by the bridge above the weighing lorry, and in position to receive material from a lifting bucket, a lifting bucket mounted on the bridge for delivering the product either 50 from a boat or from a source of supply on the dock to the receiving hopper, readily controllable means for gradually feeding the product as desired from the receiving
- hopper to the weighing lorry, and means for delivering the product from the weighing lorry to a car on any one of the tracks below. 55
5. In an ore handling and weighing plant adapted to weigh the ore into a car without interrupting the continuous operation of the transferring mechanism, a bridge, a series of parallel railroad tracks below the bridge, a traveling weighing lorry supported on the bridge and adapted to be moved transversely over the railroad tracks to register with a 60 car or cars on any one of several railroad tracks, a receiving hopper supported by the bridge above the weighing lorry in a fixed position relatively to the bridge and under which the weighing lorry may be located to 65 receive a charge preparatory to weighing it, means for delivering the ore to the receiving hopper, readily controllable means for gradually feeding and instantly stopping the feeding of the ore from the receiving hopper to the weighing lorry, and means for discharging the ore from the weighing lorry into a car or cars on any one of the several 70 tracks whereby the operations of transferring and weighing the ore may be carried on 75 simultaneously without the interference of either by the other.
6. In a device of the class described, a supporting structure extending transversely of a series of parallel railroad tracks below 80 said structure, a traveling weighing lorry supported by said structure and adapted to be moved transversely over the railroad tracks to register with a car or cars on any one of the several tracks, as desired, a receiving hopper fixed with relation to the supporting structure and supported by the structure above the weighing lorry, readily 85 controllable means for gradually feeding the ore from the receiving hopper to the 90 weighing lorry, and means for discharging the ore from the weighing lorry into a car or cars on any one of the several tracks. 95

In witness whereof, I hereunto subscribe my name to this specification in the presence 100 of two witnesses.
